UNITED STATES PATENT OFFICE.

THOMAS J. FEGLEY AND GEORGE O. LEOPOLD, OF PHILADELPHIA, PENNSYLVANIA,
ASSIGNORS TO NORTH BRO'S M'F'G CO., OF PHILADELPHIA, PENNSYLVANIA, A COR-
PORATION OF PENNSYLVANIA.

RATCHET MECHANISM.

Application filed March 30, 1923. Serial No. 628,770.

To all whom it may concern:

Be it known that we, THOMAS J. FEGLEY and GEORGE O. LEOPOLD, citizens of the United States, residing in Philadelphia, Pennsylvania, have invented certain Improvements in Ratchet Mechanism, of which the following is a specification.

Our invention relates to certain improvements in the construction of ratchet mechanism that is used especially in connection with hand tools, such as braces; screw drivers; drills; etc. The present invention is particularly adapted for hand braces.

One object of the invention is to provide a construction consisting of comparatively few parts, which can be readily assembled.

A further object of the invention is to provide a ball thrust bearing for the spindle and to provide means for gaining access to the spindle from the upper end.

In the accompanying drawings:

Fig. 1 is a side view of a portion of a brace and the head that encloses the ratchet mechanism;

Fig. 2 is a vertical sectional view of the head on the line 2—2, Fig. 3;

Fig. 3 is a sectional plan view on the line 3—3, Fig. 2;

Fig. 4 is a detached sectional view of the head on the line 4—4, Fig. 2;

Fig. 5 is a detached sectional view of parts of the mechanism;

Fig. 6 is a detached perspective view, showing the pawls and the spring shifter; and

Fig. 7 is an enlarged view of the upper portion of the mechanism shown in Fig. 2.

Referring to the drawings, 1 is the lower member of an ordinary hand brace. 2 is a head having a lateral extension 3 to which the member 1 is secured. The head is in the form of a shell enclosing the ratchet mechanism. In the shell is a detachable bushing 4, slotted at 5 for the reception of the pawls 6. These pawls are made as shown in Fig. 6. Each pawl has a body portion 7 and an extension 8. The extension of one pawl is opposite the extension of the other pawl. Each pawl has lateral pivot members 9, which rest in notches 10 in the bushing 4.

11 designates a spring shifter that bears upon the pawls. The shifter has a pin 12 projecting at the rear and engaging a shifter

bar 13 having its bearings in the projection 3 of the head 2. The pin 12 extends through the slot 14 in the shell. In the walls of the slot are notches 15. On the shifter are projections 16, which enter these notches and frictionally hold the shifter in any of its three positions.

17 designates a spindle located in the bushing 4. On this spindle are ratchet teeth 18 with which the pawls engage. On the outer end of the spindle 17 is a chuck 19, of any suitable type, for holding the screw driver, or drill bit. On the inner end of the spindle is a ball bearing illustrated in the enlarged view, Fig. 7. In the end of the spindle is an annular groove 20. In the ring 21 is an annular groove 20^a. Located in these grooves are balls 22. The ring is held to the end of the spindle by a screw 23. The bushing 4 is held from turning in the head 2 by means of a key 24, which is adapted to a keyway 25 formed in the inner wall of the head and a keyway 26 formed in the wall of the bushing. The bushing 4 has a shoulder 27 at its lower end fitting against the head 2. At the upper end of the head is a screw thread to receive the threaded cap 28. Between the cap and the upper end of the bushing is a plate 29 having a projection 30, which extends into the keyway 25, preventing the plate turning when the spindle is turned. The spindle 17 is reduced at 31. This reduced portion extends through a plug 32 screwed into the lower end of the head 2 so that the spindle is confined between this plug and the cap. The body of the chuck 19 is secured to the reduced portion of the spindle by a pin 33, or other fastening.

The operation of the ratchet mechanism is as follows: When it is desired to turn the tool intermittently in one direction, the shifter bar is depressed, moving one of the pawls into engagement with the ratchet teeth 18 and lifting the other pawl clear of the ratchet teeth.

When it is desired to move the spindle intermittently in the opposite direction, the shifter bar is moved to the other extreme position, holding out the first mentioned pawl and yieldingly holding the other pawl in engagement with the ratchet teeth.

When it is desired to lock the spindle to the head, the shifter bar is moved to the

central position, which allows the teeth to be engaged by both pawls, then the spindle can be rotated in either direction with the head.

5. When it is desired to remove the spindle from the head, all that is necessary is to unscrew the plug and withdraw the spindle. In order to gain access to the upper end of the spindle, all that is necessary is to 10 move the cap 28.

We claim:

15. The combination in ratchet mechanism, of a hollow head; a bushing secured in the head, said bushing being slotted at one side from end to end, the bushing having notches at each end at each side of the slot; a spindle mounted in the bushing, said spindle having ratchet teeth; means for holding the spindle in position; pawls pivotally mounted in the notches and arranged to engage the ratchet teeth of the spindle; a shifter bearing upon the pawls; and a shifter bar connected to the shifter and mounted in the head.

25. The combination in ratchet mechanism, of a head, said head having a screw thread at one end; a bushing located in the head and slotted at one side; a spindle located in the bushing and having ratchet teeth; a 30 plug screwed into one end of the head; a cap screwed into the other end of the head and holding the spindle in position; pawls engaging the ratchet teeth; and means for engaging the pawls.

35. The combination in ratchet mechanism, of a head, said head having a screw thread at one end; a bushing in the head, said bushing being slotted at one side and having a flange at its lower end bearing upon 40 a shoulder in the head; a spindle mounted in the bushing, said spindle having ratchet teeth; a threaded plug secured to one end of the head and through which the spindle

extends; a cap screwed into the opposite end of the head; pawls pivotally mounted in the 45 notches of the bushing and arranged to engage the ratchet teeth of the spindle; a shifter bearing on the pawls; and a shifter bar connected to the shifter.

4. The combination of a head having a 50 lateral extension; a flanged bushing mounted in the head and slotted at one side; a longitudinal key extending through key-ways in the head and in the bushing and preventing the bushing turning in the head; a spindle, having ratchet teeth, mounted in the bushing, said spindle having a reduced portion at one end; a plug having an opening through which the reduced portion of the spindle extends, said plug being secured to one end of the head; a cap secured to the opposite end of the head; pawls pivotally mounted in the slot of the bushing; a spring shifter having a pin thereon; and a shifter bar connected to the pin, said shifter bar having its bearings in the extension of the head.

5. The combination in ratchet mechanism, of a head; a slotted bushing mounted in the head and having a flange at its lower end engaging a shoulder in the head; a spindle mounted in the bushing, said spindle having ratchet teeth; a plug secured to one end of the head and a cap secured to the opposite end of the head and holding the spindle in 70 position; pawls mounted on the bushing and arranged to engage the teeth of the spindle; a spring shifter for the pawls having a rearwardly extending pin; a shifter bar engaged by the pin; a ball bearing on the inner end of the spindle; a plate between the ball bearing and the cap; and means for preventing the plate turning with the spindle.

THOMAS J. FEGLEY.
GEORGE O. LEOPOLD.
